UNITED STATES PATENT OFFICE

STANTON I. CHARLESWORTH, OF CLEVELAND HEIGHTS, AND ARCH W. HARRIS, OF CLEVELAND, OHIO

LABORATORY DISTILLATION APPARATUS

Application filed June 16, 1931. Serial No. 544,878.

Our invention relates to a distillation apparatus for laboratory use in testing light oils, benzol products and the like.

The apparatus generally used for such tests 5 incorporates a Bunsen burner to heat a test flask connected to a distillation tube, the burner's flame being regulated so that the distillation proceeds at a predetermined rate, and finally being extinguished, at the proper time, 10 so that the dry point of the liquid under test may be ascertained. Because of the open flame involved such apparatus is necessarily excluded from buildings in which volatile liquids are stored in any quantity, resulting 15 in the inconvenience that the tests must generally be conducted at points remote from the source of supply. In any event, these tests are always attended by a certain explosion risk, and any air disturbance will cause the 20 flame to waver so as to result in inaccurate results.

One of our objects is to provide an apparatus for conducting such tests without the necessity of an open flame. Another object is 25 to provide a novel distillation apparatus. Other objects may later become apparent.

In the drawing:

Figure 1 is an end elevation of an example 30 of the distillation apparatus constructed in accordance with our invention.

Figure 2 is a side elevation of the apparatus shown by the first figure.

Figures 3 to 6 are enlarged views of various details shown by Figures 1 and 2, Figures 4 35 and 6 being in cross section.

Having reference to this drawing, the specific example of our invention there shown comprises a steam manifold 1 from which a plurality of vertical cylindrical conduits 2 40 lead. These conduits have control valves 3 for regulating the admission of steam to their interior.

The conduit to the left, referring to Figure 1, has its top end closed by a hollow body 4 45 having a deep concave surface 5 for receiving the bottom and a goodly part of the side of a test flask 6. The flask has its top stoppered and provided with a thermometer 7, and is in connection with a distilling tube 8 extending 50 thru a water tank 9 and over a graduate 10.

This last arrangement is particularly illustrated in connection with the extreme right hand conduit, but it is the same throughout our apparatus.

Some of the pure solvents may be completely 55 distilled during the test, and accurate results obtained without a sudden diminishing of the heat used, but it is often necessary to cause a quick heat change to obtain the dry point of the liquid under test. In the first 60 case the apparatus just previously described may be used, but in the latter case some means of causing a quick heat change is necessary.

This is accomplished by the arrangement 65 shown in connection with the two conduits to the right. Each of these has its top end closed by a hollow cylindrical body 11 having a concave depression 12 for receiving the bottom of a test flask 6, a threaded collar 14 being fixed to the bottom of this body. A cylindrical member 15 is slidably fitted to the body above the ring 14, an enlarged skirt 16 depending therefrom over and in screw threaded engagement with the collar. This member has an outstanding annular flange 70 17 at its top and handles 18 radiating out from its skirt. The flasks are arranged and provided for distillation purposes in each instance in the manner already described.

When a test has reached the point where 80 the heat is to be diminished, the handles 18 are used to rotate the member 15 and screw it up so that the flange 17 will engage and lift the test flask up from the heating surface. As the flask is made of glass and this member 85 of metal, there will be little tendency of the latter to rotate the former, as little friction will result between the two. The distillation rate may also be varied in this manner as well as by the use of the valves 3.

Although we have shown and described a specific example of our invention in accordance with the patent statutes, we do not intend to limit the scope of our invention there- 90 to, except as defined by the appended claims. 95

We claim:

1. In a distillation apparatus, a hollow body, means for conducting heat into said body, and means carried by said body for supporting a flask, said means being adjustable 100

to vary the approach of the flask to said body.

2. In a distillation apparatus, a hollow body having a flask receiving depression, means for conducting heat into said body, a flask engaging member surrounding the depression in said body, and means for moving said member away from and towards this depression.

3. In a distillation apparatus, a hollow body having a substantially straight side and a flask receiving depression in one end, means for conducting heat into said body, a flask engaging member surrounding the depression and partially extending down the straight side of said body, and means for adjustably moving said member along the straight side of said body.

4. In a distillation apparatus, a hollow cylindrical body having a flask receiving depression in one end, means for conducting heat into said body, and a cylindrical member arranged about said body in screw threaded engagement therewith and having an annular flask engaging flange at its end approximate 25 to the depression in the end of said body.

5. In a distillation apparatus, a vertically positioned cylindrical body having a flask receiving depression in its top end, means for conducting heat into said body, a cylindrical member fitted about said body in screw threaded engagement therewith and having an annular flask engaging flange at its top end, and handles fixed to said member.

6. In a distillation apparatus for laboratory use, a steam manifold, and a plurality of vertical conduits leading from said manifold and having their upper ends closed and constructed to provide a concave surface for receiving the bottom of a test flask, at least 40 one of said conduits having a vertically movable flask engaging member surrounding its upper end, and means for moving said member.

7. In a distillation apparatus for laboratory use, a steam manifold, and a plurality of vertical conduits leading from said manifold and having their upper ends closed and constructed to provide a concave surface for receiving the bottom of a test flask, at least 50 one of said conduits having a vertically movable flask engaging member surrounding its upper end in screw threaded engagement therewith.

8. In a distillation apparatus for laboratory use, a steam manifold, and a plurality of vertical cylindrical conduits leading from said manifold and having their upper ends closed and constructed to provide a concave surface for receiving the bottom of a test flask, at least one of said conduits having a vertically movable cylindrical member surrounding its upper end, said member having an annular flask engaging flange at its top end and being in screw threaded engagement 60 with said conduit.

9. In a distillation apparatus for laboratory use, a steam manifold, a vertical cylindrical conduit leading from said manifold and having its upper end closed and constructed to provide a concave surface for receiving the bottom of a test flask, a cylindrical member closely fitting the upper end of said conduit for sliding movement and in screw threaded engagement therewith the top of this member being arranged approximate to the concave surface of said conduit and having an annular outstanding flange, and hand grasping means on said member so that same may be manually adjusted by rotation to cause vertical movement thereof so that said annular flange may adjustably engage with and vary the approach of a test flask to the concave surface of said conduit thereby adjustably varying the heat exchange therebetween.

In testimony whereof, we have hereunto set our hands.

STANTON I. CHARLESWORTH.
ARCH W. HARRIS.
